ROTARY TOOL

Harold C. Reynolds, Athens, Pa., assignor to
 Ingersoll-Rand Company, Jersey City, N. J., a
 corporation of New Jersey

Application July 5, 1935, Serial No. 29,811

4 Claims. (Cl. 74—354)

This invention relates to rotary tools, and more particularly to a reversing mechanism for tools of this type.

One object of the invention is to transmit and 5 translate the rotary movement of a uni-directional motor to a driven shaft for driving it in either direction.

Other objects will be in part obvious and in part pointed out hereinafter.

10 In the drawing accompanying this specification and in which similar reference numerals refer to similar parts,

Figure 1 is an elevation, partly in section, of a 15 rotary tool equipped with reversing mechanism constructed in accordance with the practice of the invention,

Figure 2 is a transverse view taken through Figure 1 on the line 2—2 showing the reversing mechanism in neutral position,

20 Figure 3 is a view similar to Figure 2 showing the reversing mechanism in a holding position to connect the drive and driven shafts, and

Figure 4 is an elevation, in section, taken through Figure 3 on the line 4—4.

25 Referring more particularly to the drawing, 20 designates a rotary tool comprising a pair of casing parts 21 and 22 which may be connected together in end to end relationship by bolts 23. The casing 22 constitutes a front head for the 30 rotary tool, and on the rear end of the casing 21 is a back head 24 having a grip portion 25 wherein is arranged a throttle lever 26 to control the admission of power medium, such as compressed air, into the tool.

35 The rear end of the casing 21 serves as a housing for a motor 27 of the uni-directional pressure fluid actuated type. The motor comprises a cylinder 28 and a rotor 29 having a shaft 30 which extends forwardly of the cylinder 28 and into a gear chamber 31 in the casing 21. In the rotor 29 are a series of slots 32 to accommodate vanes 33 against which pressure fluid may act for actuating the rotor.

40 The portions of the shaft 30 extending beyond the ends of the rotor 29 may be seated in anti-friction bearings of which one, designated 34, is arranged in an internal wall 35 in the casing 21.

45 Clamped between the casing parts 21 and 22 is a plate 36 having a hub portion 37 which is recessed in its opposite ends to receive anti-friction bearings 38 for a driven shaft 39 which extends forwardly through the casing 22 and may terminate in a shank 40. The shank 40 extends 50 into a socket 41 of a working implement 42 and

a pin 43 keys the working implement to the shank.

The working implement 42 is shown as being in the form of a socket wrench adapted to engage a nut 44 threaded on a bolt 45. Preferably, the 5 shaft 39 is arranged coaxially with the shaft 30, and suitable bearings (not shown) may be arranged in the front end of the casing 22 to support the shaft 39.

55 The reversing mechanism, constructed in accordance with the practice of the invention, is conveniently arranged within the gear chamber 31 to oscillate about a transmission shaft 46 of which the ends are arranged in anti-friction bearings 47 seated in the wall 35 and the plate 36. 10 The shaft 46 carries a gear 48 which is in constant mesh with a pinion 49 on the rotor shaft 30, and on an intermediate portion of the shaft 46 is a pinion 50 to mesh with transmission gearing adapted to connect the pinion 50 with a gear 20 51 on the rear end of the shaft 39.

15 The transmission gearing is carried by a support plate 52 journaled in the casing 21 and comprises a plurality of idler gears 53, 54 and 55 grouped about the pinion 50. Each pinion 53, 25 54 and 55 is rotatable about a shaft 56 seated in the support plate 52, and the pinion 53 is in constant mesh with the pinion 50 and positioned to be shifted into intermeshing engagement with the gear 51. The idler gear 54 meshes with the 30 pinion 50 and the gear 55, and the latter gear is positioned to mesh with the gear 51 in a limiting position of the plate 52.

25 The support plate 52, which is adapted to oscillate about the shaft 46 to bring the gears 53 and 55 into mesh with the gear 51, is seated with its periphery in a recess 57 in the inner surface of the casing 21. The plate 52 is of generally cylindrical shape and its peripheral surface may constitute a bearing surface 58 which 40 seats against the side surface 59 of the recess 57.

35 On the top of the plate 52 is a cover 60 to retain the gears 53, 54 and 55 within the plate 52 and also to serve as bearings for the upper ends of the shafts 56. The cover 60 is fastened 45 to the plate 52 by screws 61 and engages a shoulder 62, constituting a rear bounding surface of the recess 57, for retaining the plates 52 and 60 and thus the gears carried by the plate 52 50 in the correct assembled positions with respect to the pinion 50 and the gear 51.

40 Means are provided for shifting the support plate 52 in order to move the gears 53 and 55 into engagement with the gear 51. The support plate 52 is accordingly provided with a 55

radial slot 63 to accommodate and guide a shoe 64 which is bored to receive a pin 65 arranged eccentrically on a shaft 66 in the plate 36. On the outer end of the shaft 66 is a grip portion 67 which lies exteriorly of the casing of the tool for shifting the plate 52.

On the free end of the pin 65 is a collar 68 to serve as a seat for a spring 69 disposed about the pin 65 and seating against the shoe 64 to normally hold the shaft 66 against endwise movement.

To the end that the shoe 64, and thus the plate 52, may be held in the limiting positions the grip portion 67 is provided with a spring-pressed plunger 70 to engage indentations 71 and 72 in the outer surface of the plate 36. The indentations 71 and 72 are so located that when the plate 52 is shifted to place the gear 53 or the gear 55 in mesh with the gear 51 the plunger 70 will engage one of the indentations 71 or 72 to hold the shaft against unauthorized rotary movement.

The operation of the device is as follows: Let it be assumed that the motor 27 is constructed to rotate in a clockwise direction, as the motor is viewed from the operator's position, and that it be desired to unthread the nut 44 from the bolt 45. In such case the shaft 66 is rotated in a counter-clockwise direction for approximately a quarter of a turn from the neutral position illustrated in Figure 2. This movement of the shaft 66 causes the plate 52 to oscillate about the shaft 46 and the gear 53 to mesh with the gear 51. The motor may then be set in operation and the resulting movement of the shaft 39 will effect the removal of the nut 44 from the bolt 45.

Should it be desired to secure the nut 44 to the bolt 45 the shaft 66 is rotated in a clockwise direction. This movement of the shaft will shift the plate 52 to bring the gear 55 into mesh with the gear 51 and to disengage the gear 53 from the gear 51. The shaft 39 will then rotate in a direction for threading the nut 44 to the bolt.

I claim:

1. In a rotary tool, the combination of a casing and a uni-directional motor, a bearing surface on the casing, a drive shaft driven by the

motor and having a pinion, a driven shaft having a gear, a support member seated on the bearing surface and being shiftable in the casing, idler gears carried by the support member and being constantly rotated by the pinion, and means for shifting the support member on the bearing surface to selectively bring certain of the idler gears into mesh with the first mentioned gear for determining the direction of rotation of the driven shaft.

10

2. In a rotary tool, the combination of a casing and a uni-directional motor, said casing having a recess in its inner surface, a drive shaft driven by the motor and having a pinion, a driven shaft having a gear, a support plate seated in and rotatable in the recess, idler gears mounted on the support plate and being rotated by the pinion, and means for shifting the support plate to limiting positions to selectively bring the idler gears into mesh with the first mentioned gear for determining the direction of rotation of the driven shaft and to lock the support plate in such limiting positions.

15

3. In a rotary tool, the combination of a casing and a uni-directional motor, a drive shaft driven by the motor and having a pinion, a driven shaft having a gear, a support plate rotatable about the drive shaft, a bearing on the inner surface of the casing for the support plate, idler gears mounted on the support plate and being rotated by the pinion, and means for rotating the support plate to selectively bring certain of the idler gears into mesh with the first mentioned gear for determining the direction of movement of the driven shaft.

35

4. In a rotary tool, the combination of a casing and a uni-directional motor, a drive shaft driven by the motor and having a pinion, a driven shaft having a gear, a support plate rotatable about the drive shaft and having a slot, idler gears carried by the support plate and being rotated by the pinion, a shoe slidably in the slot, and an eccentric member for actuating the shoe in the slot to rotate the plate and thereby selectively place certain of the idler gears in mesh with the first mentioned gear for determining the direction of rotation of the driven shaft.
